UNITED STATES PATENT OFFICE.

JAMES C. COVERT, OF WATERVLIET, NEW YORK.

DESIGN FOR A SNAP-HOOK.

SPECIFICATION forming part of Design No. 26,732, dated March 9, 1897.

Application filed January 29, 1897. Serial No. 621,244. Term of patent 14 years.

To all whom it may concern:

Be it known that I, JAMES C. COVERT, a citizen of the United States, residing at Watervliet, in the county of Albany and State of New York, have invented and produced a new and original Design for Snap-Hooks; and I do hereby declare the following to be a full, clear, and exact description of the same, reference being had to the accompanying drawings, forming a part thereof.

This invention relates to a new and original design for snap-hooks and in the peculiar shape and relative arrangement of parts shown in the accompanying drawings.

15 In the drawings, Figure 1 is a side elevation of the hook. Fig. 2 is a bottom plan, and Fig. 3 is a rear end elevation.

20 A designates the body or shank, having the curved sides B, and C designates the hook portion. Extending rearwardly from the end of the body is the clamp portion D, which forms, substantially, a continuation of the body and a portion of the sides. The cross-section of this portion D is substantially U

shape, and its edges have a series of indentations d therein. The sides of the clamp portion are parallel or substantially in line with the sides B, while the bottom is in line with the bottom of the body.

The essential features of the design are the body having curved sides and the clamp portion forming continuations thereof, all substantially as shown.

It is to be understood that slight variations can be made in the design without departing 35 from the invention.

Having thus described the invention, what is claimed as new, and desired to be secured by Letters Patent, is—

The design for a snap-hook substantially as 40 shown and described.

In testimony whereof I affix my signature in presence of two witnesses.

JAMES C. COVERT.

Witnesses:

ARTHUR B. STEWART,
FRED W. COVERT.
